UNITED STATES PATENT OFFICE.

EDWIN SCOTT VOTEY, OF SUMMIT, NEW JERSEY, ASSIGNOR TO THE AEOLIAN COMPANY, A CORPORATION OF CONNECTICUT.

PIANISSIMO DEVICE FOR PIANOS.

1,313,141.

Specification of Letters Patent.

Patented Aug. 12, 1919.

Application filed August 23, 1916. Serial No. 116,488.

To all whom it may concern:

Be it known that I, EDWIN S. VOTEY, a citizen of the United States, residing at Summit, New Jersey, have invented certain new and useful Improvements in Pianissimo Devices for Pianos, of which the following is a specification.

My present invention relates to a novel combination of means in a piano-action for advancing the hammers to the strings for softer playing and for correspondingly taking up the lost motion thereby produced in the hammer-action. Further this is accomplished in an automatic piano without collapsing the striker pneumatics which by remaining open, are at the best advantage to do their work rapidly and effectively whatever may be the position of the hammer rest-rail. The full features and advantages 20 of my invention will be apparent to those skilled in the art from an understanding of the following description in connection with the drawings.

These show only one of the specific embodiments my improvements may take, these being conveniently illustrated in connection with a grand piano action. Further they illustrate my improvements in connection with only one hammer action, it being understood that all the other hammer-actions 30 are present.

Figure 1 is a side elevation of a grand piano action embodying my improvements, the parts being shown positioned with the 35 hammer rest-rail in its lowermost position; Fig. 2 is the same except that the parts are shown as positioned when the rail has advanced the hammers toward the strings.

Describing now the specific devices of the drawings:—1 is the key-bed, 2 is a piano-key pivotally supported on the pin 3, 4 is the capstan screw in the rear-end of the key; 5 is a piano-string; 6 its damper; 7 is the damper operating mechanism, of which no 45 detailed description need be given because it forms no part of my present invention. 8 and 9 are stationary front and back action-rails respectively. The hammer-action may be of any usual or preferred form, that 50 shown may therefore be briefly described as comprising a hammer 10 pivoted to the front action rail, wippen 11 pivoted at 12 to the rear action rail, also the usual jack 13, repeating lever 14, jack-abutment 15, felt-

roller 16 on the shank of the hammer for 55 engagement with the end of the jack, etc.

Coming now more specifically to my own improvements:—17 is a hammer rest-rail extending under the shanks of the hammers, said rail having a forwardly extending-arm 60 18 at each end whose free ends are pivoted at 18^a to the front action rail. 19 is a short rearwardly extending arm from each end of the rest-rail pivotally connected to a depending link 20, the lower ends of said links being connected by a cross-rod 21 running parallel with the rest-rail. 22 is a link, one at each end, which pivotally connects said cross-rod 21 with the key-bed. Thus the described 65 system of arms and links form a means by 70 which the rest-rail 17 may be raised and lowered to adjust the hammers suitably to the strings by pushing or pulling, as the case may be, on the rod 23 to swing the bell-crank 24 about its pivotal support 25 so that its toe 75 26 in contact with the cross-rod 21 lifts the rest-rail and hammers or reversely permits them to fall back away from the strings. Only the rear end of the operating rod 23 is 80 shown, the forward end being supposed to 85 come out to the front of the instrument for convenient operation by the player of the instrument.

When the rest-rail is raised, the lost motion between the jacks 13 and the felt rollers 85 16 on the hammers is taken up by means as follows:—27 is a horizontal rail supported for vertical reciprocation on the face of the action-rail 9 and resting on the above described links 22. A plurality of compression-springs 28 keep the rail 27 depressed against the tops of the links 22. 29 is a lever, which for convenience may be called a transmitting lever, one for each wippen 11, operatively connected by its middle portion to 90 its wippen by a link 30. The rear ends of all the transmitting levers are pivotally supported at 29^a on flanges secured to and carried by the rail 27. The underside of each wippen forward of its link 30 is felted at 95 29^b to receive the capstan-screws 4 in playing the piano by hand. On the other hand, in automatic playing the attack of the striker-pneumatics 31 conveniently takes place under the forward ends of the transmitting levers 29, 31^a being the movable board of the striker-pneumatic having an extension 32 cooperating with a regulating 100 105

button 33 on the transmitting lever. 34 is a stop preventing the weight of the hammer action from opening the striker pneumatics beyond their normally open operating position.

The described mechanism takes up the lost motion in the hammer-action when the hammer rest-rail is raised and does this without introducing any lost motion between the striker pneumatics and the transmitting levers as follows:—Thus comparing Fig. 2 with Fig. 1, the former showing the rest-rail advanced, it will be seen that the links 22 have also raised the rail 27 which in turn has lifted the rear ends of the transmitting levers 29, which swing upwardly about their forward ends resting on and remaining in undisturbed relationship with the extensions 32 on the movable boards of the striker-pneumatics. Finally through the links 30, this upward adjustment of the transmitting levers lifts correspondingly the wippens 11 and jacks 13 to keep the ends of the latter in operating contact with the felt rolls 16 on the hammers and otherwise eliminates any lost motion in the hammer-actions in spite of the advancement of the hammers toward the strings. Striker pneumatics are most sensitive and positive in their action when acting from their fully open operating position to a partially or half-way closed position. Thus by my improvements, said pneumatics are always acting under their best working condition regardless of the adjustment of the rest-rail.

What I claim is:—

1. In combination with the actions of a piano, each comprising a hammer, a jack and a wippen; a transmitting lever for each action operatively related to its wippen; striker pneumatics operatively related to and supporting the forward ends of the respective transmitting levers; and means which adjusts the distance of the hammers from the strings and correspondingly adjusts the rear ends of the transmitting levers to take-up the lost motion in the actions.

2. In combination with the actions of a piano, each comprising a hammer, a jack and a wippen; a transmitting lever for each action operatively related to its wippen; striker pneumatics operatively related to and supporting the forward ends of the respective transmitting levers; means which adjusts the distance of the hammers from the strings and correspondingly adjusts the rear ends of the transmitting levers to take-up the lost motion in the actions, and a link connection between each transmitting lever and its wippen by which they are operatively related as aforesaid.

3. In combination with the actions of a piano, each comprising a hammer, a jack and a wippen; a transmitting lever for each action operatively related to its wippen;

striker pneumatics operatively related to and supporting the forward ends of the respective transmitting levers; means which adjusts the distance of the hammers from the strings and correspondingly adjusts the rear ends of the transmitting levers to take-up the lost motion in the actions, and a link connection between each transmitting lever and its wippen by which they are operatively related as aforesaid, said link being located at the middle portion of the transmitting lever.

4. In combination with the actions of a piano, each comprising a hammer, a jack and a wippen; a transmitting lever for each action operatively related to its wippen; striker pneumatics operatively related to and supporting the forward ends of the respective transmitting levers; means which adjusts the distance of the hammers from the strings and correspondingly adjusts the rear ends of the transmitting levers to take-up the lost motion in the actions, a link connection between each transmitting lever and its wippen by which they are operatively related as aforesaid, said link being located at the middle portion of the transmitting lever; and piano-keys arranged to attack the underside of the transmitting levers in front of their connection with said links. 95

5. In combination with the actions of a piano, each comprising a hammer, a jack and a wippen; a transmitting lever for each action operatively related to its wippen; striker pneumatics operatively related to and supporting the forward ends of the respective transmitting levers; means which adjusts the distance of the hammers from the strings and correspondingly adjusts the rear ends of the transmitting levers to take-up the lost motion in the actions; and stop means preventing the weight of the actions on the striker-pneumatics from opening them beyond their normally open, operating position. 100

6. In combination with the actions of a piano, each comprising a hammer, a jack and a wippen; a transmitting lever for each action extending under and in the same direction as its wippen; a link for each action connecting its wippen with the middle portion of its transmitting lever; a horizontal rail extending transversely under the actions, said rail pivotally supporting the rear-ends of all of the transmitting levers; a pivotally supported rearwardly extending arm upon which said rail rests; striker-pneumatics operating on the front ends of the transmitting levers; means for yieldingly pressing said rail downwardly; means for lifting said rail-supporting arm; a hammer rest-rail; and an operating connection between said supporting arm and the hammer rest-rail raises and lowers the rest-rail from the raising and lowering of said arm. 110 120 125 130

7. In combination with the actions of a piano, each comprising a hammer, a jack and a wippen; a transmitting lever for each action extending under and in the same direction as its wippen; a link for each action connecting its wippen with the middle portion of its transmitting lever; a horizontal rail extending transversely under the actions, said rail pivotally supporting the rear-ends 10 of all of the transmitting levers; a pivotally supported rearwardly extending arm upon which said rail rests; striker-pneumatics operating on the front ends of the transmitting levers; means for yieldingly pressing said rail downwardly; means for lifting said 15 rail-supporting arm; a link extending upwardly from said rail-supporting arm, said link being pivotally connected at its upper end with the hammer rest-rail; and said operatively supported hammer rest-rail. 20

In testimony whereof I have signed my name to this specification this 22d day of August, 1916.

EDWIN SCOTT VOTEY.
